United States Patent Office

Des. 220,638
Patented May 4, 1971

220,638

PLATE OR THE LIKE

Ottorino N. Mercadante, Corning, N.Y., assignor to Corning Glass Works, Corning, N.Y.

Filed May 1, 1970, Ser. No. 22,756

Term of patent 14 years

Int. Cl. D7—01

U.S. Cl. D44—15

The figure is a top plan view of a plate of conventional configuration showing my new design.

I claim:

The ornamental design for a plate or the like, as shown and described.
